UNITED STATES PATENT OFFICE.

WALTER S. EDGE AND RUSSELL C. OLMSTED, OF NEW YORK, N. Y.

REINFORCED CONCRETE CONSTRUCTION.

Application filed June 24, 1924. Serial No. 722,004.

This invention relates to reenforced concrete construction such as is used, for example, in building roads, sidewalks, floors and walls for buildings and the like.

5 The primary object of our invention is to provide means whereby the necessary reinforcing structures or "mats" may be constructed easily and cheaply in the field, and in such a way as to impart to them a high 10 degree of rigidity and permanency.

A more specific object of our invention is to provide pressed metal chairs which are adapted to be used in conjunction with reenforcing bars and "bar ties" in the production of mats having the characteristics above mentioned.

A further object is to provide chairs of this character which will support either one or two layers of reenforcing rods.

20 Still other objects of our invention will appear more fully hereinafter.

Referring to the drawings:

Fig. 1 shows a reenforcing mat made up of two layers of bars, combined with bar ties and chairs, constructed in accordance with our invention; Figs. 2 and 3 are isometric front and rear views of one form of chair which we may employ in making a two-layer mat; Figs. 4 and 5 are a front elevation and a longitudinal sectional view, respectively, of another form of chair for a two-layer mat; Figs. 6 and 7 are similar views, respectively, of still another form of chair for a two-layer mat; Figs. 8 and 9 are similar views, respectively, of one form of chair for a single layer mat; and Figs. 10 and 11 are similar views, respectively, of another form of chair for a single layer mat.

40 As shown in Fig. 1, a mat made with the use of our improved chairs includes a plurality of bars 1 running in one direction, which we shall call, for convenience, "longitudinally," and a plurality of similar bars 2, running at right angles to the bars 1, or in other words, "transversely." Each layer of the mat is made up of a plurality of transverse and longitudinal bars tied together at points of intersection by bar-ties 3.

45 We do not claim any novelty in the use of bars and bar-ties, per se, in the making of mats, since they have been used for some time for this purpose. But what we do claim to be new is the way in which we support mats made of such parts.

55 Heretofore they have been supported in

various different ways in the construction of concrete roads, for example. One method has been to bend certain of the bars so that they form self-contained supports which, 60 when placed on the ground, support the mat in its correct position above the sub-grade. This, however, has not proved to be entirely satisfactory, since it has required the bending of some of the rods and has made 65 somewhat more difficult the fabrication of the mats in the field.

Another method of supporting the mats has been to employ removable supports adapted to be withdrawn as the concrete is 70 placed. The use of these removable supports tends, of course, to inaccuracy of work and also makes the pouring more difficult. Still another method which has been used 75 embodies the use of metal chairs, each chair being attached, usually at the factory, to two bars, one at the level of the upper layer of the mat and one at the level of the lower layer. The units thus formed are shipped to the job and there assembled into mats by 80 means of bar-ties.

By our invention we provide chairs which may be shipped in bulk to the job and there incorporated with the bars and bar-ties to form rigid self-supporting mats with a minimum of labor. These chairs, which will presently be described, are made of pressed metal and are so constructed that they may be positioned at intersections of the longitudinal and transverse bars and 85 there secured to those bars by means of the bar-ties which fasten the bars themselves together.

Chairs of this character are shown at 4 in Fig. 1, from which figure it will be apparent that the chairs are secured to the mat at points of intersection of the bars without the use of any securing means in addition to the bar-ties themselves, and with very little additional trouble. Of course, these chairs need not be placed at all intersections but only at a sufficient number to give the desired support and rigidity.

Turning now to the specific forms of chair devised by us, Figs. 2 and 3 show a chair in which the connection to the bars is off-center. This chair has a base 5 adapted to rest upon the sub-surface. Each edge of its vertical portion 6 is provided with a flange 7 to stiffen it. One edge of the vertical portion 6 of the chair is provided at 8 with a notch of sufficient size to receive the bar 1,

The vertical portion 6 is also provided at a point above the notch 8 with a slot or opening 9 through which one prong of the bar-tie 3 for the lower layer of bars is adapted 5 to pass. For attachment to the bars of the upper layer there is provided in the edge of the vertical portion of the chair another notch 10, similar to the notch 9. Also, the top of the chair is bent over in the form of 10 a lip 11 which, as shown, cooperates with the upper bar 2.

To secure the chair which has just been described to the four bars of a two-layer mat at a point of intersection, it is placed in position 15 with one of the longitudinal bars 1 in each of the two notches 8 and 10. Then the bar-ties 3 are applied in the usual manner, except that one of the prongs of the lower tie must be passed through the slot 9. It 20 thus appears that the application of the chair is accomplished with very little difficulty and with no additional securing means.

The two chairs illustrated in Figs. 4-7 25 differ from the chair above described by the fact that they are secured centrally to the intersecting bars instead of off-center. Each of these chairs is, therefore, provided with a central opening or channel 12, preferably formed by stamping out the two flanges 13 which add stiffness to the structure. At the bottom of each of these openings a lip 14 is formed, for purposes which will appear in a moment.

Referring now particularly to the chair of 30 Figs. 4 and 5, it will be noted that the opening or channel 12 is enlarged slightly at the top and that near the top the flanges 13 are interrupted at 15. The upper portions 16 of the flanges are cut to form notches 17, shown in Fig. 5, which are adapted to receive the bar-tie for the upper layer, as indicated. As is shown in the drawing, the bar-tie of the lower layer abuts against the lip 14 and its prongs pass through the slots 18. 35 In applying this chair to a two-layer mat it is placed in position from below so that the lower bar 1 rests upon the lip 14 formed at the bottom of the channel 12 and the upper bar 1 is adjacent the slot 17. The transverse 40 bars 2 rest upon the longitudinal bars 1 in each layer, as shown. The bar-tie 3 for the lower layer is positioned as already described and bent around the longitudinal bar 1 in the usual manner. The bar-tie 3 of the upper 45 layer is positioned in the notches 17 under the bar 1, which is adjacent those notches. It is then passed over the bar 2 and bent around under the bar 1 in the usual manner.

50 The chair of Figs. 6 and 7 is identical with the chair of Figs. 4 and 5 in so far as the construction at the lower end of the channel 12 is concerned. Its upper end differs from the upper end of the chair of Figs. 4 and 5 55 in that there are no notches formed in the

flanges 13 or 16 for receiving the bar-tie. On the contrary, the bar-tie 13 embraces the bottom of the bar 1 directly and thence passes over the bar 2 and down around the bar 1 in the usual manner. Relative vertical 70 movement between the bars and the chair is prevented by the presence of the lips 19 which are formed at the top of the chair and which overlie the bar 2.

As pointed out in connection with the chair of Figs. 2 and 3, it should be noted that with the chairs of Figs. 4-7, also, the tying of the chair and bars together is accomplished with a minimum of labor.

The two chairs of Figs. 8-11 differ from the previously described chairs primarily by the fact that they are adapted for use with a single layer mat. Their construction and operation will be apparent from an inspection of the drawings in conjunction with the above description of the two-layer forms of chairs. The principal difference between the chair of Figs. 8 and 9 and the chair of Figs. 10 and 11 is that in the former the channel 12 is formed with flanges 21 and is provided at its lower extremity with a slotted straight lip 22 for receiving the bar-tie, whereas the channel 20 of the chair of Figs. 10 and 11 has no flanges 21 and its lip 22 is curved to conform to the shape of the bar-tie.

The advantages of our improved device have been indicated. Particular attention is called to the fact that the chairs which have been described above may be made cheaply, by simple and efficient methods of production, may be shipped to the job in bulk independently of the bars and ties, and may be applied to the mats formed of the bars and ties with as great or little frequency as desired and at almost no additional expense. It should be pointed out, also, that the addition of such chairs not only provides a positive support for the mat, insuring its being held at the proper level, but also adds strength and rigidity to the reinforcement as a whole.

The terms and expressions which we have employed are used as terms of description and not of limitation, and we have no intention, in the use of such terms and expressions, of excluding any equivalents of the features shown and described, or portions thereof, but recognize that various modifications are possible within the scope of the invention claimed.

What we claim is:

1. A reinforcing mat for concrete structures comprising a plurality of longitudinal and transverse bars arranged in two layers, the bars of each layer being secured together at points of intersection by bar-ties and a plurality of supporting chairs distinct from the bar ties secured to said bars at points of intersection by certain of said bar-ties.
2. A reinforcing mat for concrete struc-

- tures comprising a plurality of longitudinal and transverse bars arranged in two layers. the bars of each layer being secured together at points of intersection by bar-ties, and a 5 plurality of supporting chairs distinct from the bar ties secured to said bars at points of intersection by certain of said bar-ties, each of said chairs being thus secured to both of said layers.
- 10 3. A chair for use with reenforcing structures made of two layers of intersecting bars and in which the bars of each layer are secured together at points of intersection by bar-ties, said chair comprising a base and a 15 vertical portion, said vertical portion being recessed to receive one bar of each layer adjacent a point of intersection, and so constructed that the chair may be secured to said bars and the bars intersecting there- 20 with by the same bar-ties that secure said intersecting bars together.
4. A chair for use with reenforcing structures made of intersecting bars secured together at points of intersection by bar-ties, 25 said chair comprising a base and a vertical portion; said vertical portion being provided with a recess in its top surface for receiving one of said bars adjacent a point of intersection of two of them, and being also pro- 30 vided with a horizontally extending lug at the bottom of said recess against which a bar-tie is adapted to abut in securing said intersecting bars together and to said chair.
5. A chair for use with reenforcing structures made of intersecting bars secured together at points of intersection by bar-ties, 35 said chair comprising a base and a vertical portion, said vertical portion being provided with a recess in its top surface for receiving one of said bars adjacent a point of inter- 40 section of two of them, and being also pro-
- vided with a horizontally extending lug at the bottom of said recess against which a bar-tie is adapted to abut in securing said intersecting bars together and to said chair, 45 and with means adjacent said recess for preventing the bar-tie from falling into it.
6. A chair for use with reenforcing structures made of intersecting bars secured together at points of intersection by bar-ties, 50 said chair comprising a base and a vertical portion, said vertical portion being provided with a recess in its top surface for receiving one of said bars adjacent a point of intersection of two of them, and being also 55 provided with a horizontally extending lug at the bottom of said recess against which a bar-tie is adapted to abut in securing said intersecting bars together and to said chair, the top surface of said vertical portion being provided with notches adjacent said recess, for the reception of parts of said bar-tie.
7. A chair for use with reenforcing structures made of intersecting bars secured together at points of intersection by bar-ties, 65 said chair comprising a base and a vertical portion, said vertical portion being provided with a recess in its top surface for receiving one of said bars adjacent a point of intersection of two of them, and being also provided with a horizontally extending lug at 70 the bottom of said recess against which a bar-tie is adapted to abut in securing said intersecting bars together and to said chair, and with horizontally extending vertical flanges for preventing the bar-tie from falling into said recess.
